UNITED STATES PATENT OFFICE

FRANZ EIBL, OF FINOW, GERMANY, ASSIGNOR TO AJAX ELECTROTHERMIC CORPORATION, OF AJAX PARK, NEW JERSEY, A CORPORATION OF NEW JERSEY

INDUCTION ELECTRIC FURNACE CONSTRUCTION

Application filed June 30, 1930, Serial No. 464,808, and in Germany December 31, 1929.

My invention relates to water cooled inductor coils for electric furnaces.

A purpose of my invention is to form an inductor coil having an interior water carrying passage whose walls are initially continuous throughout, without the necessity of closing an opening or joining surfaces by soldering, brazing, or otherwise.

A further purpose is to fold longitudinally continuous tubing so as to concentrate a considerable part of the metal at one side of the tubing and leave an interior passage at the other side, and to wind the tubing with the folded side inward to form a water cooled inductor coil.

A further purpose is to avoid danger of leakage from a water cooled inductor coil under conditions of abnormally high heating.

Further purposes will appear in the specification and in the claims.

It has previously been recognized that the current density per unit cross sectional area in an inductor coil of an induction furnace increases from a minimum near the periphery to a maximum at the inside of the coil. With this fact in view, it has been suggested that the bulk of the metal in the inductor coil intended to carry the current be concentrated near the inside of the coil, and only sufficient metal be placed near the periphery to form the walls of suitable passages for the cooling medium. This has the further advantage that in case of leakage the water will escape near the outside of the inductor, instead of at the inside, where it might produce an explosion.

Inductor coils previously designed to concentrate the greater part of the metal near the interior of the coil, and carry the water along the outside, have been built up by attaching tubes to the outside of the coil, or by slotting the outside edge of the coil and securing a strip along this edge. In any case, it has been necessary that brazing, soldering, welding or some similar means of attachment be used.

While brazing, welding, and other similar methods of attachment may be satisfactory under some conditions, I find that very fre-

quently the inductor coil becomes highly heated. At such times these methods are likely to fail, with consequent leakage of water, which, in spite of every precaution, may come in contact with the heated crucible and cause the furnace to explode.

By my invention the portion of the inductor coil carrying the greater part of the current, as well as the portion forming the walls of the water carrying passages, are integral, and all danger of failure of any portion of the wall due to high heating of the inductor coil (below the point of actual melting) is avoided.

Furthermore, I obtain a much greater facility of construction and cheapness of manufacture than is possible with an inductor formed by brazing, soldering, or welding. And since the efficiency of cooling of the inductor coil depends to a considerable extent upon the ease with which heat is conducted through the metal parts of the coil to the point of water cooling, my structure attains very high thermal transmission efficiency because all parts of the metal wall are in equally intimate contact, instead of having a soldered portion, for example, which will conduct heat less readily.

Figure 1 is a vertical central section, partly diagrammatic, of an induction furnace to which my invention is applied.

Figure 2 is an enlarged fragmentary view corresponding generally to Figure 1.

Figure 3 shows in fragmentary perspective a sectioned turn of my inductor coil.

The inductor 10 is supplied with current from a conventional power source 11 through the lines 12 and 13. Power factor correction may very desirably be provided as by the condenser 14. The crucible 15, within the inductor coil 10, holds the charge.

Water cooling connections to the inductor coil may be made at any point along its length, preferably at 16 and 17 to the top and the bottom of the coil.

The individual turns of the inductor coil 10 are formed of preferably seamless tubing which has been folded at points 18, 19 and 20 to concentrate the greater part of the metal at the inside of the inductor coil, at the same

time leaving a passage 21 formed between the end 22 of the fold 19 and the outer edge 23 of the original tubular stock. In order to permit close winding of the turns, the outer edges have been bent as at 24 and 25 so that the width of the turn will be no greater at the outside than at the inside.

It will be evident that variations and modifications in the folding or crimping of the inner edge may be made to concentrate a relatively greater or relatively smaller portion of the entire tube wall on the inner conductor portion of the turn. On the other hand, the walls of the water carrying passage 21 may be formed in any way which is desired, by varying the shape of the folds 24 and 25, or by increasing or reducing the number of folds, or by filleting the edges or progressively curving the walls in any of the manners familiar to designers.

I have described the method here shown as my best form because it permits close winding of the turns, with water cooling which should ordinarily be adequate, and sufficient concentration of the current carrying capacity near the inside of the coil to provide for the increased current density at that point.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:

- 40 1. In an electric induction furnace, an inductor coil having tubular integral walls folded upon themselves at the inside of the coil, leaving an interior passage near the periphery of the coil.
- 45 2. In an electric induction furnace, a continuous seamless tube crimped at one side to concentrate the metal at that point, having an interior passage displaced toward the other side, and wound into a coil with the crimped edge inward.
- 50 3. In an electric induction furnace, an inductor coil of a rectangular cross section having its lateral walls crimped at the inside edge to form the inner edge of an interior passage of rectangular cross section.

FRANZ EIBL.
